Atty.

UNITED STATES PATENT OFFICE

HOWARD C. LESLIE, OF MILTON, MASSACHUSETTS, ASSIGNOR TO B R E MANUFACTURING CO., OF HYDE PARK, MASSACHUSETTS, A CORPORATION OF MASSACHUSETTS

HINGE CONNECTION FOR WATER-CLOSET SEATS AND COVERS

Application filed May 9, 1929. Serial No. 361,734.

This invention relates to water closets and particularly to the means of connecting the seat and cover to a hopper, the object of the present invention being the production of a hinge connection for both the seat and cover which may be connected thereto without the use of screws or similar securing devices.

This object is attained by the mechanism illustrated in the accompanying drawings.

10 For the purpose of illustrating the invention, one preferred form thereof is illustrated in the drawings, this form having been found to give satisfactory and reliable results, although it is to be understood that the various 15 instrumentalities of which the invention consists can be variously arranged and organized, and the invention is not limited to the precise arrangement and organization of these instrumentalities as herein shown and 20 described except as required by the scope of the appended claims.

Of the drawings

Figure 1 represents a plan of a toilet seat and cover secured to the hopper by hinge connections embodying the principles of the present invention.

Figure 2 represents a side elevation of the same, and

Figure 3 represents a rear elevation of the same shown partly in section on line 3, 3, on Fig. 2.

Similar characters indicate like parts throughout the several figures of the drawing.

35 In the drawings, 10 is a water closet hopper of usual construction having the rearwardly extending shelf 11.

This shelf 11 has cylindrical holes 12 extending therethrough to receive the threaded shanks 13 of vertical posts 14.

On the lower end of each shank 13 is a washer 15 of resilient material and a nut 16 by which said vertical posts may be securely 45 clamped to the shelf 11.

Each post 14 has a laterally extending cylindrical socket 17 formed in its upper end and when the posts 14 are clamped to the shelf 11 these sockets 17 are in alinement facing each other.

The seat 18 has a rear extension 19, the opposite sides of which are flat and parallel.

To these opposite flat sides of the extension 19 are secured metal plates 20.

The inner face of each plate 20 has two 55 separated cone-shaped projections 21 which are adapted to be positioned in the extension 19 and lock said plate in position.

Each plate 20 has an opening 22 therein and the outer face of each plate is provided with 60 a cylindrical recess 23 concentric with the cylindrical opening 22.

This recess 23 is of the same diameter as the socket 17 in the post 14.

Fitted to the socket 17 and projecting into 65 the recess 23 is a sleeve 24.

A tubular member 25 projects through the extension 19 and each of the sleeves 24 and has its opposite ends upset as indicated at 26 to form shoulders abutting the outer ends of the 70 sleeves 24 to retain them in the recesses 23.

The cover 27 also has a rear extension 28 in the opposite flat sides of which are disposed the metal sockets 29 having flanges 30 thereon to accurately position them in said 75 extension.

Each metal plate 20 has projecting from its inner face a cone-shaped lug 31 which is fitted to the metal socket 29.

These lugs 31 are in actual alinement and 80 form a pivot about which the cover 27 may be moved when it is desired to raise it from the seat 18.

The flanged ends 30 bear against the inner face of the metal plates 20 and prevent the 85 wooden cover 27 from becoming worn by the constant raising and lowering of said cover.

Each post 14 has a flat face 32 surrounding the sleeve 24 and bearing against the outer face of the metal plate 20.

As the metal plates 20 are always in contact with the flat faces 32 of the posts 14 all lateral movement of the seat is prevented.

This is also true of the cover 27 inasmuch as the outer ends of the flanged metal sockets 95 29 are always in contact with the inner flat faces of the metal plates 20.

The seat when raised or lowered moves about the axis of the tubular member 25 and when raised or lowered carries the cover 27 100

therewith, though said cover 27 may be raised and lowered about the axis of the lugs 31 without moving the seat.

This gives a very rigid construction of hinged connections for the seat and cover of a water closet.

One particular advantage of the construction is that no screws of any kind are necessary in the connection between the seat and cover and between the vertical supporting post 14.

Where screws are used the constant use of the seat and cover soon loosens the same which is a great disadvantage.

Another advantage of the present construction is that the exposed surfaces of the post 14 and plates 20 may be enameled or covered in some other manner to give a better finish to the hinge connections than would otherwise be obtained.

It is believed that the operation and many advantages of the invention will be understood without further description.

Having thus described my invention, I claim:

1. In a water closet, two separated vertical posts having sockets facing toward each other; a seat having an extension between said posts; a metal end plate at each side of said extension having a recess in the outer face thereof; a sleeve fitted to each socket with one end extending into said recess; and a member extending through the seat and both sleeves with its opposite ends upset over the outer ends of said sleeves.

2. In a water closet, two separated vertical posts having sockets facing toward each other; a seat having an extension between said posts; a metal end plate at each side of said extension having a recess in the outer face thereof; a sleeve fitted to each socket with one end extending into said recess; and a member extending through the seat and both sleeves with its opposite ends upset over the outer ends of said sleeves.

3. In a water closet, two separated vertical posts having sockets facing toward each other; a seat having an extension between said posts; a metal end plate at each side of said extension having a recess in the outer face thereof, said plates each having two projections anchored in said extension; a sleeve fitted to each socket with one end extending into said recess; and a member extending through the seat and both sleeves with its opposite ends upset over the outer ends of said sleeves.

4. In a water closet, two separated vertical posts having sockets facing toward each other; a seat having an extension between said posts; a cover having a rear extension; a metal end plate at each side of said extension having a recess in the outer face thereof and a cylindrical lug projecting into the cover extension; a sleeve fitted to each socket

with one end extending into said recess; and a member extending through the seat and both sleeves with its opposite ends upset over the outer ends of said sleeves.

5. In a water closet, two separated vertical posts having sockets facing toward each other; a seat having an extension between said posts; a cover having a rear extension; a metal end plate at each side of said extensions having a recess in the outer face thereof and a cylindrical lug projecting into the cover extension; a sleeve fitted to each socket with one end extending into said recess; a member extending through the seat and both sleeves with its opposite ends upset over the outer ends of said sleeves; and a metal socket anchored in the cover extension to receive said lug.

6. In a water closet, two separated vertical posts having sockets facing toward each other; a seat having an extension between said posts; a cover having a rear extension; a metal end plate at each side of said extensions having a recess in the outer face thereof and a cylindrical lug projecting into the cover extension; a sleeve fitted to each socket with one end extending into said recess; a member extending through the seat and both sleeves with its opposite ends upset over the outer ends of said sleeves; and a flanged metal socket anchored in the cover extension to receive said lug.

7. In a water closet, a seat having a rear extension; metal end plates at the opposite sides of said extension; a cylindrical member extending through said extension and projecting beyond the opposite sides thereof and having shoulders at opposite ends; and a sleeve surrounding each projecting end and retained in position thereon by said shoulders.

8. In a water closet, a seat having a rear extension; metal end plates at the opposite sides of said extension each having a cylindrical recess in the outer face thereof; a cylindrical member extending through said extension and projecting beyond the opposite sides thereof and having shoulders at opposite ends; and a sleeve surrounding each projecting end with one end disposed in one of said recesses and retained in position thereon by said shoulders.

9. In a water closet, a seat having a rear extension; metal end plates having lugs extending into the opposite sides of said extension; and a cylindrical member extending through said extension and end plates, and having shoulders at opposite ends engaging said end plates to retain said lugs in said extension.

10. In a water closet, a seat having a rear extension; metal end plates at the opposite sides of said extension; a cylindrical member extending through said extension and projecting beyond the opposite sides thereof and having shoulders at opposite ends; and a cylindrical element surrounding each pro-

jecting end between the outer face of each end plate and one of said shoulders.

11. In a water closet, two separated vertical posts having sockets facing toward each other; a seat having an extension between said posts; a cover having a rear extension; a metal end plate at each side of said extension having formed integral therewith a cylindrical lug extending into the cover extension; a cylindrical element projecting from each end plate and fitted to each socket; said elements being in alinement and a member extending through the seat extension and both cylindrical elements with its opposite ends upset over the outer ends of said cylindrical elements.

12. In a water closet, two separated vertical posts having sockets facing toward each other; a seat having an extension between said posts; a cover having a rear extension; a metal end plate anchored to each side of said seat extension having a cylindrical lug extending into the cover extension and an outwardly extending cylindrical projection fitted to each socket, the projection on one plate being in alinement with the projection on the other plate; and a member extending through the seat extension and both cylindrical projections with its opposite ends upset over the outer ends of said projections.

30 Signed by me at 294 Washington St., Boston, Mass., this 7th day of May, 1929.

HOWARD C. LESLIE.
